UNITED STATES PATENT OFFICE.

ALBERT WILLIAM HORN, OF CHICAGO, ILLINOIS.

CONTINUOUS AUTOMATIC GRAVITY-DISCHARGE REHEATING-FURNACE.

1,380,102.

Specification of Letter's Patent.

Patented May 31, 1921.

Application filed April 21, 1920. Serial No. 375,537.

To all whom it may concern:

Be it known that I, ALBERT W. HORN, a citizen of the United States, residing at Chicago, in the county of Cook and State of Illinois, have invented certain new and useful Improvements in Continuous Automatic Gravity-Discharge Reheating-Furnaces, of which the following is a description.

My invention belongs to that general class 10 of apparatus designed to reheat billets of metal during the process of manufacture.

It has for its object the production of apparatus simple and effective in operation, whereby the billets may be more equably 15 heated throughout all their parts during the passage through the reheating furnace.

To this end it consists in the novel construction, arrangement and combination of parts herein shown and described and more 20 particularly pointed out in the claims.

In the drawings, wherein like reference characters indicate like or corresponding parts,

Figure 1 is a central vertical longitudinal 25 section through a reheating furnace illustrating my invention;

Fig. 2 is a horizontal section substantially on line 2—2 of Fig. 1;

Fig. 3 is a transverse section substantially 30 on line 3—3 of Fig. 2;

Figs. 4 and 5 are detailed views illustrating one form of heating members; and

Fig. 6 is a vertical longitudinal section partly broken away, illustrating more fully 35 my improved furnace and the sub-chamber coöoperating therewith.

In the drawings, 1 indicates the top of my improved furnace and 2 the bottom of the reheating chamber. The skids 3 are 40 arranged substantially parallel to one another, and are composed of pipes which are kept sufficiently cooled by water forced therethrough. These pipes are supported upon suitable abutments 4 arranged at intervals, and are preferably inclined upward 45 from the point where the billets enter the furnace to the point where they are discharged. The abutments 4 are spaced from one another, and between them I arrange a 50 series of preferably communicating pits 5, which in the preferred construction are provided with outer closures 6. 7 indicates the billets passing through the furnace, propelled by suitable means exterior to the furnace, the billets being pushed forward in a column substantially as indicated.

The skids 3 are continued up toward the discharge end of the furnace, and are there preferably bent inwardly as at 8, thence downwardly as at 9, thence horizontally as 60 at 10, thence upwardly as at 11, and thence inclined downward as at 12, so that the billets will be discharged by gravity, passing beneath a pivoted closure 13. It will be seen that the discharging inclined skids, 65 as at 12—12, are not in alinement with the main portion of the skids 3—3, but are offset therefrom. Arranged in a forward chamber are suitable heating members 14, arranged in alinement with the parts 3—3 70 of the skids. The wall 15 is sectional, as shown, providing two end sections and a central section with a space between the center and the end sections in the line with the parts 3 of the skids and the heating members 14. The billets are forced forward on the skids 3, and upon reaching the sectional wall or hot bottom 15, are forced forward thereover to the inclined discharging skids. At that point the bottom of the billets for- 80 merly in contact with the skids 3—3 are over the pits 16—16 and the heat from the heating members 14 is directed thereon.

It is thus clear that that portion of the billets coming in contact with the cooled 85 skids 3—3 is not permanently heated to the same extent as the other portions, causing what is termed a "black spot", and which affects the finished product unless effectually removed. This is removed, by my im- 90 proved device, as the temperature at the particular spots mentioned is brought up to the same temperature as the balance of the billets.

17 indicates one or more of the heating 95 members for the furnace, the same being positioned above the billets as indicated.

In this form of furnace, as indicated, a greater portion of the heat normally tends to seek the upper part of the furnace and the upper part of the billets, and it is desirable that suitable means be provided for increasing the temperature below the lower surface of the billets.

This I prefer to accomplish by a suitable 105 arrangement of heating members positioned below the lower surface of the billets as indicated.

18 indicates preferably a series of air pipes within which are positioned suitable 110 conducting pipes 19 for the heating medium. The pipes 19 are controlled by valves 20

positioned outside the furnace, so that the heat may be regulated as desired. The air pipes supply the necessary atmospheric air for proper combustion, the flames being projected through an inturned section of the pipe 19 as indicated. The pipes 18 and 19 are projected through the walls of the furnace, the first one at the left coöperating with the burners 14. The next to the right 10 may, if preferred, terminate in simple heating members at each side of the walls, directing the flame into the pit 5. Arranged at intervals, the pipe 18 may be extended substantially through from side to side of the furnace, as indicated at 21, and be provided with a plurality of burners or heating members, as at 22, preferably directing the heat upward at an inclination so that it will contact with the lower surface of the billets, 20 as indicated.

Any preferred or well known means may be employed for securing and controlling the proper regulation of the air. In the preferred use, the air is heated in the usual manner prior to being delivered into the furnace.

As illustrated in Fig. 6, the draft above the billets is indicated as toward the right, and is drawn downward through the flue 23, and thence through the plurality of openings 24 in the rear wall into the heating chamber 25, thence through the plurality of openings 26 in the opposite end wall 27, thence through a flue 28, and finally 30 to a stack 29, where it is discharged into the atmosphere. The incoming air is introduced at a suitable port as at 30 and thence through a tortuous passage 31, passing about suitable baffle plates 32, and is finally 35 discharged into a suitable flue 33, which conducts the air through the various leads of pipe 34, supplying the air pipes 18, and the burners 19.

If desired, the passing current of heated 45 air below the billets may be conducted by a separate flue 35 discharging into the stack 29. Any preferred means may be employed for controlling the several flues. The flue 35 may be provided with a movable damper 36 and the flue 28 with a similar damper 37. The air delivered to the intake flue 30 is preferably under pressure, any preferred means, as at 38, being employed for this purpose.

55 The mode of operation is apparent. The billets are delivered as indicated at the right hand end of the furnace in a continuous column by feeding means arranged outside the furnace. They are pushed up the skids 3 and the intervening wall 15, and are thus delivered by gravity alone by means of the inclined extension 12, escaping beneath the automatic door 13.

The incoming air necessary for proper 60 combustion is forced through the flue 30

into a tortuous passage 31 arranged in the chamber 25, the air being heated by reason of the high temperature maintained in the chamber 25. After thus being heated, the air is delivered through the flue 33 and conducted to the various heating members as stated, that below the line of billets being preferably delivered through the flue 35 to the stack 29.

The heat delivered above the billets, as at 70 17, is maintained in any preferred manner, and passing rearward, serves to maintain the top of the furnace at a high temperature.

That portion of the lower surfaces of the billets resting upon the skids 3 and those 80 cooled by contact therewith, is reheated as they pass over the pits 16 and the heating members 14.

The entire apparatus is very effective in 85 operation and the billets may be delivered preheated to substantially the same temperature throughout, and thus avoiding the defects caused by the "black spots" before referred to.

Having thus described my invention, it is 90 obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In an apparatus of the kind described, 100 a reheating furnace provided with cooled skid members for the billets, said skids at a suitable point being offset and continued out of alignment with the preceding part thereof, in combination with means for admitting a heating medium above the advancing billets, and independent means for directing a heating medium upon the advancing billets upon the lower surface thereof 105 at the points where said billets were previously in contact with the skid members.

2. In an apparatus of the kind described, 110 a reheating furnace provided with cooled skid members for the billets, said skids at a suitable point being offset and continued out of alignment with the preceding part thereof, in combination with means for directing a heating medium in the space above the advancing billets, independent means 115 for directing a heating medium in the space beneath the advancing billets and means for directing a heating medium upon the lower surface of the advancing billets at the points where said billets were previously in contact with the skid members.

3. In an apparatus of the kind described, 120 a reheating furnace provided with cooled skid members for the billets, said skids at a suitable point being offset and continued 125

- out of alinement with the preceding part thereof, in combination with means for directing a heating medium above the advancing billets, independent means for directing 5 a heating medium below the advancing billets, and means for directing a heating medium upon the lower surface of the advancing billets at the points where said billets were previously in contact with the skid 10 members.
4. In an apparatus of the kind described, a reheating furnace provided with cooled skid members for the billets said skids at a suitable point being offset and continued 15 out of alinement with the preceding part thereof, in combination with means for directing a heating medium, both above and below the advancing billets, means for regulating said heating medium, and means in- 20 dependent of said first named means for directing a heating medium upon the lower surface of the advancing billets at the points where said billets were previously in contact with the skid members.
5. In a device of the kind described, a re- 25 heating chamber provided with longitudinally extending cooled skid members, said skid members at a point near the discharge end being extended inward toward each 30 other and out of alinement with the preceding portion of said members, and thence outward and being downwardly inclined to discharge the billets, in combination with independent heating members arranged to di- 35 rect the heating mediums substantially in line with the parallel skid members and upon the lower surface of the billets at the points where said billets were previously in contact with the skid members.
6. A device of the kind described, com- 40 prising a reheating chamber provided with longitudinally extending cooled skid members, offset during their course to uncover the contact points of the billets therewith, 45 means for admitting heat above said billets and independent means for directing a heating charge upon said uncovered parts.
7. A device of the kind described, com- 50 prising a reheating furnace provided with longitudinally extending cooled skid members for the advancing billets, means for admitting a heating medium above the billets, and independent means for admitting the heating medium at a plurality of points 55 beneath the advancing billets.
8. A device of the kind described, com- prising a reheating chamber provided with longitudinally extending parallel cooled skid members for the advancing billets, means for additionally heating that portion 60 of the billets which had previously rested upon the skids, means for admitting a heating medium above the billets, means for independently admitting a heating medium below the billets, and means for regulating 65 said heating medium.
9. A device of the kind described, comprising a reheating furnace provided with longitudinally extending parallel cooled skid members for the advancing billets, 70 means for admitting a heating medium above the billets, in combination with means for admitting a heating medium below the billets in a horizontal direction, and additional means for admitting a heating medium be- 75 low the billets in an upwardly inclined direction.
10. In an apparatus of the kind described, a reheating furnace provided with longitudinally extending parallel cooled skid mem- 80 bers, means for admitting a heating medium above the skid members, and means for admitting a heating medium below the skid members, in combination with means for causing a circulation of the said heating me- 85 dium in the furnace, and independent means for controlling the circulation of the heating medium above and below the billets.
11. A device of the kind described, com- 90 prising a reheating furnace provided with cooled skid members for the advancing billets, means for admitting a heating medium above the billets, and means independent of said first named means for admitting a heating medium beneath the advancing billets. 95
12. A device of the kind described, com- prising a reheating furnace provided with cooled skid members for the advancing billets, means for admitting a heating medium above the billets, and means for admitting 100 a heating medium beneath the advancing billets, said last named means being adapted to be regulated independently of said first named means.
- In testimony whereof, I have hereunto 105 signed my name in the presence of two sub- scribing witnesses.
